REVERSE CYCLE HEATING SYSTEM

Alwin B. Newton, Minneapolis, Minn., assignor to
 Minneapolis-Honeywell Regulator Company,
 Minneapolis, Minn., a corporation of Delaware

Application August 14, 1939, Serial No. 289,939

13 Claims. (Cl. 62—4)

This invention relates to an automatic control system for a reverse cycle heating system having heating means in the form of a condenser for dissipating heat to a space for heating the same, an evaporator for absorbing heat from the outside air and a mechanism for circulating refrigerant through the condenser and evaporator.

An object of this invention is to provide first control means for controlling the mechanism to maintain desired conditions in the space along with second control means for automatically defrosting the evaporator to cause most efficient operation of the system, the arrangement being such that when the second control means is causing defrosting of the evaporator the first control means is ineffective to operate the mechanism.

A further object of this invention is to terminate the defrosting cycle as soon as the evaporator has been defrosted whereby the first control means may immediately control the mechanism as soon as the evaporator has been defrosted.

Another object of this invention is to initiate the defrosting cycle at definite timed intervals and terminate the cycle as soon as the evaporator has been defrosted.

Still another object of this invention is to provide a control means responsive to the pressure on the high pressure side of the system for preventing the building up of excessive pressures in the system.

Another object of this invention is to provide heating means for heating the evaporator during the defrosting cycle to hasten the defrosting action and preferably the system is so arranged that the heating means is only effective when the first control means is demanding heat.

Other objects and advantages will become apparent to those skilled in the art upon reference to the accompanying specification, claims and drawing in which:

Figure 1 is a diagrammatic illustration of one form of this invention, and

Figure 2 is a diagrammatic illustration of a modified control system that may be substituted for the control system of Figure 1.

Referring now to Figure 1, the space or enclosure to be heated is designated at 10 and is provided with an outside wall 11. The space 10 is heated by an air conditioning unit 12. Return air is drawn from the space 10 through a return air duct 13 and fresh air is drawn from outside of the space through a fresh air duct 14, the fresh air and the return air being mixed

and passed over a heating coil which may take the form of a condenser 18. A fan 15 operated by a motor 16 draws the mixture of fresh air and return air over the heating coil 18 and discharges the heated air through a discharge duct 17 into the space 10. Refrigerant is circulated through the condenser 18 by a refrigerating apparatus generally designated at 20 which may comprise a compressor 21 operated by an electric motor 22. Compressed refrigerant is discharged from the compressor 21 through a high pressure line 23 to the condenser 18 and condensed refrigerant is collected in a receiver 24. Liquid refrigerant flows from the receiver 24 through a liquid line 25 into an evaporator 26 located outside of the space 10. Evaporated refrigerant is withdrawn from the evaporator 26 through a suction line 27 by the compressor 21. The flow of refrigerant to the evaporator 26 may be controlled by a thermostatic expansion valve 28 having a thermal bulb 29 responding to the temperature of the refrigerant leaving the evaporator 26. Heating means which may be in the form of strip heaters 30 are provided for heating the evaporator 26 under certain conditions to hasten the defrosting action of the evaporator 26. The structure thus far described is conventional in the art and therefore a further description thereof is not considered necessary, it being sufficient to state that when the compressor 21 is placed in operation heat is absorbed by the evaporator 26 and is liberated by the condenser 18 for heating the space 10.

The compressor motor 22 and hence the compressor 21 and the heating means 30 for the evaporator 26 are controlled by a temperature responsive controller 32 responding to the temperature within the space 10 and by a relay generally designated at 33. The relay 33 is controlled by a unitary control arrangement 34 responsive to the pressure in the condenser 18 and hence the temperature of the condenser and to the pressure in the evaporator 26 and hence to the temperature of the evaporator 26. The relay 33 may also be controlled by a timer generally designated at 35.

The temperature responsive controller 32 may comprise a bellows 38 charged with a volatile fluid for operating a lever 39 against the action of an adjustable tension spring 40 for operating a mercury switch 41. For purposes of illustration, it is assumed that when the temperature within the space 10 decreases to 70° the mercury switch 41 is closed, and when the temperature increases to 72° the mercury switch 41 is opened.

The relay generally designated at 33 may comprise an operating coil 43 for operating a switch arm 44 with respect to contacts 45 and 46. When the operating coil 43 is energized, the switch arm 44 is moved into engagement with contact 45, and when the operating coil 43 is deenergized the switch arm 44 is moved into engagement with the contact 46 by means of springs, gravity, or other means, not shown.

The unitary control arrangement 34 may be of the type shown and described in application Serial No. 196,447, filed by Albert L. Judson and Carl G. Kronmiller on March 17, 1938. For purposes of illustration in this application, the unitary control arrangement 34 is shown to include a control device 48 responsive to changes in pressure in the evaporator 26, a control device 49 responsive to changes in pressure in the condenser 18, and a relay 50 controlled by the two control devices.

The control device 48 may comprise a bellows 52 connected by a pipe 53 to the suction line 27 so that the bellows 52 is operated in accordance with changes in evaporator pressure or temperature. The bellows 52 operates a lever 54 pivoted on a fulcrum member 55 against the action of an adjustable tension spring 56. One end of the tension spring 56 is connected to the lever 54 and the other end is connected to an adjusting screw arrangement 57. The lever 54 carries an insulating pad 58 upon which is mounted a bridge member 59. The bridge member 59 carries a contact 60 which is adapted to be moved into engagement with a contact member 61 carried by a terminal 62. The bridge member 59 also carries a contact 63 which is adapted to be moved into engagement with a contact member 64 carried by a terminal 65. Concentrically arranged cams 66 and 67 are provided for independently positioning the contact members 61 and 64 with respect to the contacts 60 and 63. For purposes of illustration, it is assumed that when the suction pressure, that is, the pressure in the evaporator 26, increases to 0 pounds the contact 60 is first moved into engagement with the contact member 61, and when the pressure increases to 33 pounds the contact 63 is moved into engagement with the contact member 64. Upon a decrease in pressure, the contact 63 first disengages the contact member 64 at 33 pounds and then the contact 60 disengages the contact member 61 at 0 pounds. The pressure value at which the contact 60 engages and disengages the contact member 61 will be determined by the climatic conditions and it is desirable to adjust this value to correspond to a temperature value about 15 or 20° below the coldest weather which is liable to occur in that particular locality. An evaporator pressure of 0 pounds as illustrated herein corresponds to a temperature value of 22° below zero. Therefore the design temperature of the particular locality will be approximately 5° below zero.

The control device 49 may comprise a bellows 69 connected by a pipe 70 to the high pressure line 23 so that the bellows 69 is expanded and contracted in accordance with changes in pressure or temperature in the condenser 18. The bellows 69 operates a lever 71 fulcrumed on a fulcrum member 72 against the action of an adjustable tension spring 73. One end of the tension spring 73 is connected to the lever 71 and the other end is connected to an adjusting screw arrangement 74. Adjustably mounted on the lever 71 is an abutment member 75 formed of insulating material and provided with abutment surfaces 76 and 77. The abutment surface 76 is adapted to en-

gage a contact member 78 carried by a terminal 79 to move the contact member 78 out of engagement with a contact 80. The abutment surface 77 is adapted to engage a contact member 81 carried by the terminal 65 for moving the contact member 81 out of engagement with a contact 82. For purposes of illustration, it is assumed that as the pressure in the condenser increases the contact member 81 is moved out of engagement with the contact 82 at 150 pounds and then the contact member 78 is moved out of engagement with the contact 80 at 200 pounds. Upon a decrease in pressure, the contact member 78 first engages the contact 80 at 200 pounds and then the contact member 81 engages the contact 82 at 150 pounds.

The relay 50 may comprise an operating coil 85 for operating bridge members 86 and 87. When the operating coil 85 is energized, the bridge member 86 is moved into engagement with contacts 88 and 89 and the bridge member 87 is moved into engagement with contacts 90 and 91. When the operating coil 85 is deenergized the bridge members 86 and 87 are moved out of engagement with their respective contacts by means of springs, gravity, or other means, not shown. The unitary control arrangement 34 may also be provided with a terminal 92 to facilitate wiring connections.

The timer 35 may comprise a rotor 95 influenced by a field winding 96. The rotor 95 operates a cam 98 through a reduction gear train 97 and the cam 98 in turn operates a lever 99 which operates a mercury switch 100. The mercury switch 100 is normally closed and is opened momentarily at definite intervals by the high dwell on the cam 98. The timer 35 may open the mercury switch 100 at any desired intervals, and for purposes of illustration in this application it is assumed that the timer 35 opens the mercury switch 100 every two hours.

Power is supplied to the control system, to the compressor motor 22, and to the strip heaters 30 by means of line wires 102 and 103 leading from some source of power, not shown. It is here noted that the field winding 96 of the timer 35 is connected directly across the line wires 102 and 103 so that the cam 98 is continuously operated.

Assume now that the relay 33 is energized so that the switch arm 44 is engaging the contact 45 and that the temperature within the space 10 decreases to 70° to close the mercury switch 41. A circuit is thereupon completed from the line wire 102 through wire 105, mercury switch 41, wire 106, switch arm 44, contact 45, wire 107, compressor motor 22, and wire 108 back to the other line wire 103. Completion of this circuit energizes the compressor motor 22 and hence the compressor 21 to circulate refrigerant through the condenser 18 and the evaporator 26 to liberate heat to the space 10. When the temperature within the space 10 rises to 72° to open the mercury switch 41, the above outlined circuit is broken and the compressor motor 22 and hence the compressor 21 are stopped. In this manner desired temperature conditions are maintained in the space 10 by cyclically operating the compressor 21.

Assume now that the relay 33 is deenergized so that the switch arm 44 is engaging the contact 46. If under these conditions the temperature within the space 10 should decrease to 70° to close the mercury switch 41, a circuit is completed from the line wire 102 through wire 105,

mercury switch 41, wire 106, switch arm 44, contact 46, wire 109 through the strip heaters 30 arranged in parallel and through wire 110 back to the other line wire 103. Thus when the temperature within the space 10 is below a desired value and the relay 33 is deenergized, the strip heaters 30 are energized to hasten the defrosting action of the evaporator 26.

Assume now that the mercury switch 100 of the timer 35 is closed, that the evaporator pressure has risen to 33 pounds following defrosting of the evaporator 26 to move the contacts 60 and 63 into engagement with the contact members 61 and 64, and that the pressure in the condenser 18 has decreased to 150 pounds to move the contact members 78 and 81 into engagement with the contacts 80 and 82. Under these conditions, a circuit is completed from the line wire 102 through wire 112, mercury switch 100, wire 113, contact 80, contact member 78, terminal 79, conductor 114, terminal 62, contact member 61, contact 60, bridge member 59, contact 63, contact members 64 and 81, contact 82, conductor 115, contact 89, conductor 116, operating coil 85, conductor 117, terminal 92, and wire 118 back to the other line wire 103. Completion of this circuit causes energization of the operating coil 85 of the relay 50 to move the bridge members 86 and 87 into engagement with their respective contacts.

Movement of the bridge member 87 into engagement with the contacts 90 and 91 completes a circuit from the line wire 102 through wire 120, contact 91, bridge member 87, contact 90, wire 121, operating coil 43 of the relay 33, and wire 122 back to the other line wire 103. Completion of this circuit energizes the relay 33 to move the switch arm 44 into engagement with the contact 45 so that the space temperature responsive controller 32 may control the operation of the compressor 20. In other words, when the evaporator pressure has increased to a defrosting value of 33 pounds and the condenser pressure has decreased to 150 pounds, the relay 33 is energized to place the compressor 21 under the control of the space temperature responsive controller 32.

Movement of the bridge member 86 into engagement with the contacts 88 and 89 completes a maintaining circuit for the operating coil 85 of the relay 50 which is independent of the contact 63 and contact member 64 and the contact 82 and contact member 81. This maintaining circuit may be traced from the line wire 102 through wire 112, mercury switch 100, wire 113, contact 80, contact member 78, terminal 79, conductor 114, terminal 62, contact member 61, contact 60, bridge member 59, conductor 124, contact 88, bridge member 86, contact 89, conductor 116, operating coil 85, conductor 117, terminal 92, and wire 118 back to the other line wire 103. Completion of this maintaining circuit maintains the operating coil 85 of the relay 50 energized until either the evaporator pressure decreases to 0 pounds or the condenser pressure increases to 200 pounds. When either of these contingencies occur, the above outlined maintaining circuit is interrupted to deenergize the operating coil 85 of the relay 50 which in turn deenergizes the operating coil 43 of the relay 33. The operating coil 85 of the relay 50 and hence the operating coil 43 of the relay 33 cannot again be energized until the above outlined starting circuit is completed which occurs only when the evaporator pressure increases to 33

pounds and the head pressure decreases to 150 pounds.

It is here noted that the mercury switch 100 of the timer 35 is connected in series in both the starting and maintaining circuits of the operating coil of the relay 50 so that when the mercury switch 100 is momentarily opened the operating coil 85 is deenergized and cannot again be reenergized until such time as the evaporator pressure rises to 33 pounds and the condenser pressure decreases to 150 pounds.

The operation of Figure 1 may be summarized briefly as follows: when the evaporator pressure rises to 33 pounds indicating that the evaporator 26 has defrosted and when the condenser pressure decreases to 150 pounds, the relays 50 and 33 are energized to place the control of the compressor 21 under the control of the space temperature responsive controller 32. The space temperature responsive controller 32 then cycles the compressor 21 to maintain desired temperature conditions within the space 10. If either the switch 100 of the timer 35 is opened or if the evaporator pressure should decrease to 0 pounds indicating that a large amount of frost is present on the evaporator 26 or the pressure in the condenser 18 should become excessive, illustratively 200 pounds, then the relays 50 and 33 are deenergized to interrupt the control of the compressor 21 by the space temperature responsive controller 32. The operation of the compressor 21 is therefore stopped and the evaporator 26 is allowed to defrost. Deenergization of the relay 33 places the control of the strip heaters 30 under the control of the space temperature responsive controller 32, and if the space temperature responsive controller 32 should be calling for heat, then the strip heaters 30 are energized to hasten the defrosting action. If the space temperature responsive controller 32 is satisfied, there is no need for hastening the defrosting action since under the majority of conditions the evaporator 26 may be defrosted without the assistance of the strip heaters 30. This affords quite a saving in operating costs of this type of system. After the evaporator 26 has defrosted to cause the evaporator pressure to rise to 33 pounds and after the condenser pressure has decreased to 150 pounds, the compressor 21 is again placed under the control of the space temperature responsive controller 32 to maintain desired temperature conditions within the space 10. An important feature of this invention is that the defrosting cycle is terminated immediately after the evaporator 26 has been defrosted so that if the temperature responsive controller 32 is demanding heat the compressor may immediately be placed in operation. If it is not desirable to defrost the evaporator 26 at timed intervals, the timer 35 may be eliminated and under these conditions the evaporator will be defrosted only when a relatively large amount of frost has been built up on the evaporator 26 to cause the pressure thereof to decrease to 0 pounds. Under some conditions, this type of operation would be entirely satisfactory.

Referring now to Figure 2, there is disclosed another control arrangement which may be substituted for the control arrangement of Figure 1 for accomplishing substantially the same results as are accomplished with the control arrangement of Figure 1 with the exception that the timer for defrosting at timed intervals is omitted. In Figure 2, the compressor is designated at 22, the strip heaters at 30, and the space temperature

responsive controller at 32. The control system of Figure 2 also includes a controller 130 responsive to evaporator pressure and a controller 131 responsive to condenser pressure.

The controller 130 responsive to evaporator pressure may include a bellows 133 connected by a pipe 134 to the suction line for operating a lever 135 against the action of an adjustable tension spring 136. The lever 135 operates a mercury switch provided with left electrodes 138 and 139 and with right electrodes 140 and 141. For purposes of illustration, it is assumed that when the evaporator pressure increases to 33 pounds, the mercury switch 137 is tilted to the position shown in Figure 2 to cause bridging of the electrodes 138 and 139, and when the evaporator pressure pressure decreases to 0 pounds the mercury switch 137 is tilted to the opposite position to bridge the electrodes 140 and 141.

The controller 131 may comprise a bellows 143 connected by a pipe 144 to the high pressure line for operating a lever 145 against the action of an adjustable tension spring 146. The lever 141 operates a switch 147, and for purposes of illustration it is assumed that when the condenser pressure decreases to 150 pounds the mercury switch 147 is closed as in Figure 2, and when the pressure increases to 200 pounds the mercury switch 147 is tilted to the open position.

Power is supplied to the compressor motor 22 and to the strip heaters 30 by means of line wires 150 and 151 leading from some source of power not shown.

Assume now that the evaporator has defrosted to cause the evaporator pressure to rise to 33 pounds to cause bridging of the electrodes 138 and 139, that the condenser pressure has decreased to 150 pounds to close the mercury switch 147 and that the temperature within the space being heated decreases to 70° to close the mercury switch 41. Under these conditions, a circuit is completed from the line wire 150 through mercury switch 41, wire 152, electrodes 139 and 138, wire 153, mercury switch 147, wire 154, compressor motor 22, and wire 155 back to the line wire 151. The compressor is thereby placed in operation and remains in operation until such time as the space temperature responsive controller 32 becomes satisfied. In this manner, desired temperature conditions are maintained within the space. If the pressure on the high pressure side of the refrigerating apparatus should increase to 200 pounds the mercury switch 147 is opened to stop operation of the compressor motor 22 thereby providing safe operation of the system. If the evaporator pressure should decrease to 0 pounds indicating that a relatively large amount of frost has accumulated on the evaporator then the mercury switch 137 is tilted to the opposite position to cause bridging of the electrodes 140 and 141. This interrupts the circuit to the compressor motor 22 to stop operation of the compressor whereby the evaporator is allowed to defrost. If under these latter conditions the space temperature responsive controller 32 should demand heat then a circuit is completed from the line wire 150 through mercury switch 41, wire 152, electrodes 140 and 141, wire 156, strip heaters 30, and wire 157 back to the other line wire 151. Completion of this circuit energizes the strip heaters 30 as long as the space temperature responsive controller 32 is demanding heat to hasten the defrosting action of the evaporator. After the evaporator has been defrosted, the suction pressure rises to 33 pounds to

tilt the mercury switch 137 to the position shown in Figure 2 to again place the control of the compressor motor 22 under the space temperature responsive controller 32.

While for purposes of illustration a controller responsive to evaporator pressure and a controller responsive to condenser pressure have been disclosed, it is obvious that these controllers may respond directly to evaporator temperature or condenser temperature inasmuch as the pressure and temperature in the evaporator and condenser are coextensive. Thus this invention in its broader aspects contemplates a control device responsive to a condition which is a measure of evaporator temperature and hence accumulation of frost on the evaporator and also a controller responsive to a condition which is a measure of the temperature of the condenser. The various temperature and pressure values utilized for purposes of illustration herein are not to be construed in a limiting sense since these pressure and temperature values may be varied in accordance with different types of installations.

Although for purposes of illustration two forms of this invention have been disclosed, other forms may become apparent to those skilled in the art upon reference to this disclosure and therefore this invention is to be limited only by the scope of the appended claims.

I claim as my invention:

1. In a reverse cycle heating system for a space having an evaporator for absorbing heat, a condenser for dissipating heat for heating the space and a mechanism for controlling the circulation of refrigerant through the condenser and evaporator, the combination of, control means for normally controlling the mechanism to maintain desired temperature conditions in the space, means for periodically interrupting at regular timed intervals the control of the mechanism by the control means for defrosting the evaporator, and means for returning the control of the mechanism to the control means as soon as the evaporator has been defrosted.

2. In a reverse cycle heating system for a space having an evaporator for absorbing heat, a condenser for dissipating heat for heating the space and a mechanism for controlling the circulation of refrigerant through the condenser and evaporator, the combination of, control means for normally controlling the mechanism to maintain desired temperature conditions in the space, means for periodically interrupting at regular timed intervals the control of the mechanism by the control means for defrosting the evaporator, and means responsive to a condition which is a measure of evaporator temperature for returning the control of the mechanism to the control means as soon as the evaporator temperature increases to a value indicating that the evaporator has been defrosted.

3. In a reverse cycle heating system for a space having an evaporator for absorbing heat, a condenser for dissipating heat for heating the space and a mechanism for controlling the circulation of refrigerant through the condenser and evaporator, the combination of, control means for normally controlling the mechanism to maintain desired temperature conditions in the space, means for interrupting at timed intervals the control of the mechanism by the control means for defrosting the evaporator, and means responsive to the pressure in the evaporator for returning the control of the mechanism to the control means as soon as the evaporator pressure in-

creases to a value indicating that the evaporator has been defrosted.

4. In a reverse cycle heating system for a space having an evaporator for absorbing heat, a condenser for dissipating heat for heating the space and a mechanism for controlling the circulation of refrigerant through the condenser and evaporator, the combination of, control means for normally controlling the mechanism to maintain desired temperature conditions in the space, defrosting control apparatus for interrupting the control of the mechanism by the control means at timed intervals and when the evaporator becomes appreciably frosted to defrost the evaporator and for returning the control of the mechanism to the control means as soon as the evaporator has been defrosted.

5. In a reverse cycle heating system for a space having an evaporator for absorbing heat, a condenser for dissipating heat for heating the space and a mechanism for controlling the circulation of refrigerant through the condenser and evaporator, the combination of, control means for normally controlling the mechanism to maintain desired temperature conditions in the space, means for interrupting at timed intervals the control of the mechanism by the control means for defrosting the evaporator, means for also interrupting the control of the mechanism by the control means when the evaporator becomes appreciably defrosted, and means for returning the control of the mechanism to the control means as soon as the evaporator has been defrosted regardless of how the control of the mechanism by the control means was interrupted.

6. In a reverse cycle heating system for a space having an evaporator for absorbing heat, a condenser for dissipating heat for heating the space and a mechanism for controlling the circulation of refrigerant through the condenser and evaporator, the combination of, control means for normally controlling the mechanism to maintain desired temperature conditions in the space, means for interrupting the control of the mechanism by the control means for defrosting the evaporator and for returning the control of the mechanism to the control means as soon as the evaporator has been defrosted, and means for interrupting the control of the mechanism by the control means when the temperature of the condenser becomes excessive.

7. In a reverse cycle heating system for a space having an evaporator for absorbing heat, a condenser for dissipating heat for heating the space and a mechanism for controlling the circulation of refrigerant through the condenser and evaporator, the combination of, control means for normally controlling the mechanism to maintain desired temperature conditions in the space, means for interrupting the control of the mechanism by the control means for defrosting the evaporator, means for interrupting the control of the mechanism by the control means when the temperature of the condenser rises to a predetermined high value, and means for returning the control of the mechanism to the control means only when the evaporator has been defrosted and the temperature of the condenser decreases to a predetermined low value.

8. In a reverse cycle heating system for a space having an evaporator for absorbing heat, a condenser for dissipating heat for heating the space and a mechanism for controlling the circulation of refrigerant through the condenser and evaporator, the combination of, heating means for

heating the evaporator to hasten defrosting thereof, control means operative upon demand for heat for operating the mechanism to circulate refrigerant to maintain desired temperature conditions in the space, means for interrupting control of the mechanism by the control means for defrosting the evaporator, and means for operating the heating means while the evaporator is defrosting to hasten defrosting of the evaporator only when the control means is demanding heat.

9. In a reverse cycle heating system for a space having an evaporator for absorbing heat, a condenser for dissipating heat for heating the space and a mechanism for controlling the circulation of refrigerant through the condenser and evaporator, the combination of, heating means for heating the evaporator to hasten defrosting thereof, control means operative upon a demand for heat for operating the mechanism to circulate refrigerant to maintain desired temperature conditions in the space, means for interrupting the control of the mechanism by the control means for defrosting the evaporator and for returning the control of the mechanism to the control means as soon as the evaporator has been defrosted, and means for operating the heating means while the evaporator is defrosting to hasten defrosting of the evaporator only when the control means is demanding heat.

10. In a reverse cycle heating system for a space having an evaporator for absorbing heat, a condenser for dissipating heat for heating the space and a mechanism for controlling the circulation of refrigerant through the condenser and evaporator, the combination of, heating means for heating the evaporator to hasten defrosting thereof, control means operated upon a demand for heat for operating the mechanism to circulate refrigerant to maintain desired temperature conditions in the space, means for interrupting at timed intervals the control of the mechanism by the control means for defrosting the evaporator, and means for operating the heating means while the evaporator is defrosting to hasten defrosting of the evaporator only when the control means is demanding heat.

11. In a reverse cycle heating system for a space having an evaporator for absorbing heat, a condenser for dissipating heat for heating the space and a mechanism for controlling the circulation of refrigerant through the condenser and evaporator, the combination of, heating means for heating the evaporator to hasten defrosting thereof, control means operative upon a demand for heat for operating the mechanism to circulate refrigerant to maintain desired temperature conditions in the space, means for interrupting at timed intervals the control of the mechanism by the control means for defrosting the evaporator, means for returning the control of the mechanism to the control means as soon as the evaporator has been defrosted, and means for operating the heating means while the evaporator is defrosting to hasten defrosting of the evaporator only when the control means is demanding heat.

12. In a reverse cycle heating system for a space having an evaporator for absorbing heat, a condenser for dissipating heat for heating the space and a mechanism for controlling the circulation of refrigerant through the condenser and evaporator, the combination of, heating means for heating the evaporator to hasten defrosting thereof, control means operative upon a

demand for heat for operating the mechanism to circulate refrigerant to maintain desired temperature conditions in the space, means responsive to the formation of frost on the evaporator for interrupting the control of the mechanism by the control means to defrost the evaporator and for returning the control of the mechanism to the control means as soon as the evaporator has been defrosted, and means for operating the heating means while the evaporator is defrosting to hasten defrosting of the evaporator only when the control means is demanding heat.

13. In a reverse cycle heating system for a space having an evaporator for absorbing heat, a

5 condenser for dissipating heat for heating the space and a mechanism for controlling the circulation of refrigerant through the condenser and evaporator, the combination of, heating means for heating the evaporator to hasten defrosting thereof, control means operative upon demand for heat for operating the mechanism to circulate refrigerant to maintain desired temperature conditions in the space, means for interrupting control of the mechanism by the control means for defrosting the evaporator, and means for operating the heating means when the evaporator is defrosted.

ALWIN B. NEWTON.
